W. P. WHITE

JAR CAP OPENER

Original Filed Jan. 6, 1921

Inventor
William P. White
By his Attorney
George Ramsey

UNITED STATES PATENT OFFICE.

WILLIAM P. WHITE, OF BROOKLYN, NEW YORK, ASSIGNOR TO ANCHOR CAP & CLOSURE CORPORATION, OF BROOKLYN, NEW YORK, A CORPORATION OF NEW YORK.

JAR-CAP OPENER.

Application filed January 6, 1921, Serial No. 435,316. Renewed February 25, 1926.

To all whom it may concern:

Be it known that I, WILLIAM P. WHITE, a citizen of the United States, residing at Brooklyn, in the county of Kings, State of New York, have invented certain new and useful Improvements in Jar-Cap Openers, of which the following is a specification.

The present invention relates broadly to sealing devices and more specially to a tool 10 for removing jar caps.

The principal object of the present invention is to provide a jar cap opener for hermetic side seal caps with the handle thereof rounded to provide strength and rigidity for 15 removing tightly fitting caps.

Another object of the present invention is a jar cap opener having a semi-cylindrical handle and a reinforced jaw capable of transmitting pulling stresses on the jaw as longitudinal forces on the rounded handle portion of the opener.

Another object of the present invention is a jar cap opener having a flattened fulcrum end adapted to be seated upon the top of a 25 cap, and a rounded handle whereby the fulcrum prevents rotation of the opener in the operator's hand, and the round handle facilitates operation of the device.

A still further object of the present invention is a jar cap remover having a jaw 30 below the handle and with a reinforcement between the jaw and the handle to provide clearance for the reception of the flange of a deep skirted jar cap.

Other and further objects of the present invention will in part be obvious and will in part be pointed out hereinafter in the specification following by reference to the accompanying drawings forming a part thereof 40 and in which like parts are represented by like characters throughout the several figures thereof.

Figure 1 is a plan view looking at the bottom of the opener;

Figure 2 is a side view of the opener;

Figure 3 is a perspective view of the opener;

Figure 4 illustrates the operation of the opener on one form of hermetic seal;

Figure 5 is an enlarged detail of the 50 opener head;

Figure 6 is an end view looking at the end of the handle; and

Figure 7 is an end view looking at the end of the head of the opener.

Heretofore in the art various types of bottle openers have been provided for removing crown corks or the like from bottles. Such constructions have comprised cast metal devices having engaging lips or lugs 55 attached to the edge of the body portion of the opener, and wire devices having lips struck out from the sides of the wire; and also sheet metal devices comprising a body portion with the forward edge of the body 60 portion extending beyond the side flanges to form lips for engaging a bottle cap. Such prior art devices have been adapted for use with relatively easily removed caps and such devices have not been designed particularly 65 with the idea of utilizing maximum strength. When such devices are utilized to remove large caps such as are tightly hermetically sealed upon packing jars and the like, by being sealed under pressure on the jar, these devices have proven unsatisfactory. Where attempts have been made to increase the size 70 of the cast and wire devices to gain strength, the devices have been unsightly and unwieldy. Where attempts have been made to utilize sheet metal in making the known prior art designs into more powerful openers, the manufacturing operations become so 75 expensive as to be substantially prohibitive; and the prior art sheet metal shapes, such as flat body portions with forwardly extending flanges, are not sufficiently strong, due to the designs, unless exceedingly heavy metal is used which increases cost and quickly wears out. Furthermore in using the sheet metal 80 type of openers comprising a flat body portion with a pair of forwardly extending flanges and a rounded nose it is necessary for the operator to tightly grip the body portion to prevent the device from rolling on 85 the bottle cap or jar cap. Where such devices are utilized to uncap jars the flat body portion must be gripped with sufficient tightness as to become uncomfortable in the hand 90 of the operator.

The present invention overcomes the difficulties of the known art by providing a jar cap opener which is designed primarily with the idea of disposing of the material in the manner best to sustain the forces necessary 95 to uncap tightly sealed hermetic packages.

The present invention is designed to be utilized for uncapping various types of packages but primarily for removing such jar caps as is illustrated in the Hull Patent 1,253,492, January 15, 1918. This type of cap sets very tightly against the vessel wall and cannot be readily removed with the known openers of the prior art.

The present invention comprises a sheet metal opener having a handle portion that is rounded to fit the hand and is provided with a flat fulcrum bar adapted to rest upon the cover part of the cap in such manner as to securely seat the opener on the cap and prevent any tendency of the opener to roll in the hand of the operator. A bead engaging jaw is connected with the body portion by means of a pressed bracket, or strut, embossment whereby active cover removing forces are delivered to the handle portion of the device rather than forces which otherwise would tend to bend the bead engaging jaw.

Referring now to the drawings, the device comprises a handle 1 which is substantially semicylindrical in form and tapers slightly from the outer end toward the forward end. The forward end of the handle is provided with a pair of arms 2 and 4 which are arched to provide clearance for the flange of the cap to be removed. These arms extend forward substantially parallel and comprise the fulcrum for the operation of the device. A flat fulcrum 5 extends between the arms and maintains the arms rigidly spaced apart but permit the arms to be positively seated on the cap to be removed. Adjacent the handle and beneath the arms is provided the downwardly and forwardly extending cap engaging jaw 6. This jaw is curved to further facilitate clearance beneath the arms 2 and 4 and the jaw is joined to the handle by means of a reinforcement 7 which sustains the jaw in operation and transmits the uncapping forces to the handle 1 as longitudinal forces. This action is illustrated in Figure 5 which shows the stresses in the arms 2 and 4 as being transmitted by the arrows A to the semicylindrical handle 1, and the arrows B indicate the forces from the cap engaging jaw 6 as also being transmitted to the said semicylindrical handle. The handle being semi-cylindrical in form sustains these forces readily, particularly in view of the fact that a grasp of the hand on the handle imposes forces in the direction of the arrows C, Figure 6, which are in opposition to the un-

capping forces that tend to spread the handle. In other words, the uncapping forces tend to flatten the curvature of the forces whereas the grip of the operator tends to increase the curvature. This tool has been found to be capable of manufacture of relatively light weight materials and at the same time be sufficiently strong to remove the tightest hermetic cap without undue effort on the part of the operator.

Having thus described my invention, what I claim is:

1. An article of manufacture comprising a cap opener formed from a single piece of sheet metal and having a handle, a curved jaw beneath said handle, a reinforcement bracket comprising an embossment between said jaw and said handle and adapted to transmit forces from the jaw as compression stresses to said handle, arched fulcrum means extending forward and over said jaw and being adapted to prevent said handle from rolling when the device is in operation.

2. A cap opener comprising a semi-cylindrical handle, arched arms comprising extensions of the side walls of the handle, a cap engaging jaw offset below the bottom wall of the said handle, and fulcrum means joining the arched arms, said fulcrum means being substantially in line with the bottom wall of the handle.

3. As an article of manufacture, a cap opener stamped from sheet metal comprising a handle having a pair of arched fulcrum members extending forwardly thereof, a flat bar joining the ends of said members, and adapted to rest on the top of a cap to form a fulcrum, said bar being in substantially the same plane as the bottom of the handle, a cap engaging jaw extending downwardly below the bottom of said handle, and reinforcing means between the jaw and the bottom of the handle to minimize the bending stresses on the jaw when in use by transmitting the same to the handle as compression stresses.

4. As an article of manufacture, a sheet metal cap opener comprising a handle having a pair of arched fulcrum members extending forwardly thereof, a flat bar joining the ends of said members, and adapted to rest on the top of a cap to form a fulcrum, said bar being in substantially the same plane as the bottom of the handle, and a cap engaging jaw extending downwardly below the bottom of said handle.

WILLIAM P. WHITE.
